UNITED STATES PATENT OFFICE.

WILLIAM H. SMITH, OF OAKLAND, CALIFORNIA.

TANK-FILLING MEANS.

Application filed June 24, 1926. Serial No. 118,279.

The invention relates to mechanisms for insuring a more or less constant level of water in a tank, such as the boiler of a heating system, and such invention has reference to mechanisms which are disposed at the exterior of the tank so as to be readily accessible, easily lubricated, etc.

One object of the invention is to provide means for holding a filling valve for the tank positively in open position while it is functioning, and to make unique provision, controlled by the level of water in the tank, for automatically releasing said holding means at the proper time, provision being then made for rapidly closing the valve, so that difficulties encountered with slow-closing valves, are effectively overcome.

Another object of the invention is to provide tank filling means which will be rather simple and inexpensive, yet will be exceptionally efficient, reliable, and in every way desirable.

With the foregoing in view, the invention resides in the novel subject matter herein-after described and claimed, the description being supplemented by the accompanying drawings.

Figs. 1 and 2 are side elevations partly broken away and in section, Fig. 1 showing the invention with the tank filling valve open and positively held in open position, whereas Fig. 2 discloses the relation of parts when the valve is closed.

Fig. 3 is a top plan view.

Fig. 4 is a transverse sectional view as indicated by line 4—4 of Fig. 3.

The preferred form of construction has been illustrated, and while such construction will be rather specifically described, it is to be understood at the outset, that within the scope of the invention as claimed, various modifications may be made.

The numeral 5 designates an appropriate base from which two bearings 6 and 7 rise. Supported by one of these bearings is the terminal 8 of a water supply line 9 leading from city pressure or from other desired source, said line having a valve 10 provided with means whereby it is normally closed. 11 designates the stem of this valve, said stem being connected to a cross arm 12 from

which rods 13 rise through an appropriate guide 14, the upper ends of said rods having connection with an additional cross arm 15. Between this last named cross arm, and the 55 guide 14, a compression spring 16 is provided, said spring acting to close the valve quickly when permitted to function. Secured to and rising from the cross arm 15, is a rod 17 which is pivotally connected at 60 18 to a substantially horizontal, valve opening lever 19. This lever is disposed above the base 5 and is fulcrumed upon a supporting link 20 which rises from and is pivoted to said base. Provision is made, hereinafter 65 described, for operating this lever to open the valve 10, when the water level in the tank or boiler with which the invention is used, recedes to a predetermined extent.

Rotatably supported by the bearing 7, is 70 a pipe member 21 which is swiveled as at 22, to a pipe 23 leading to the boiler or tank with which the invention is used. Secured to the pipe member 21 is a coupling 24 having a socket 25 which receives a cylindrical projection 26 on a coupling 27 which is secured to the terminal 8, above described. A branch pipe 28 leads from this coupling to the boiler or tank and when the valve 10 is open, water under pressure travels 80 through the pipe line 9, through said valve, through the coupling 27 and through the pipe 28, to said tank or boiler.

Secured to, communicating with, and projecting laterally from the coupling 24, 85 is a short pipe 29, which pipe carries and communicates with a receptacle 30 which is spaced above the base 5, a vent pipe 31 being connected with the upper part of this receptacle, and leading to the tank or boiler, at a point above the water level. An arched frame 32 transversely straddles the receptacle 30 and is secured to the base 5, and upon the crown of this frame, a weighted lever 33 is fulcrumed, the weight 34 of 90 said lever being adjustably mounted on one of its ends, while the other end of this lever is linked as at 35, to the receptacle 30. This receptacle has a one-way connection with the valve opening lever 19, so that 100 when said receptacle is raised by the action of the weight 34 and lever 33, said lever 19

will be actuated to open the valve 10. In establishing this one-way connection, I prefer to provide a vertical rod 36, pivoted at 37 to the receptacle 30, the upper end of 5 said rod passing through an opening 38 in the lever 19 and having a shoulder 39 underlying said lever.

The end of the lever 19, associated with the rod 36, is disposed adjacent one leg of 10 the arched frame 32, and mounted on this leg, is a latch 40, said latch preferably comprising a straight vertical bar pivoted between its ends at 41 and having a notch 42 in its upper end to engage the lever 19 15 and hold the latter in valve-open position. The pivot 41 is rather loose, and an over-balancing arm 43 projecting from the latch 40 may therefore be relied upon to engage said latch with the lever 19. When this 20 latch and lever are engaged with each other as shown in Fig. 1, the lower end of said latch is inclined and is in the downward path of a projection 44 on the receptacle 30, it being remembered that this receptacle 25 is now in an elevated position, the water level in it and in the tank or boiler are rather low and the valve 10 is being positively held open. As the water level in the tank or boiler rises, it flows through the 30 pipe 23, swivel connection 22, pipe member 21, coupling 24 and pipe 29, into the receptacle 30, and the weight of the water collecting in this receptacle, causes it to gradually 35 lower against the action of the lever 33 and weight 34. By the time the receptacle is about full of water, the pin 44 has released the latch 40 as shown in Fig. 2. Thus the lever 19 is quickly freed and the spring 16 then immediately acts to close the valve 10. 40 It may here be further explained that during the gradual downward movement of the receptacle 30 while the lever 19 is held by the latch 40, the rod 36 moves downwardly with respect to said lever 19, said rod then 45 sliding through the opening 38. When the latch releases the lever however, and the valve 10 closes, said lever again assumes an operative relation with the shoulder 39. Thus, as the water level in the receptacle 30 50 lowers, due to corresponding lowering of the liquid level in the tank or boiler, the weighted lever 33-34, will again raise said receptacle, and during this raising movement, shoulder 39 will move lever 19 to valve-open position. When this position of 55 the lever 19 is reached, the latch 40 engages said lever and holds it to maintain the valve in a completely open position, until said latch is again tripped by the projection 44. 60 It will be seen from the foregoing that the invention, while being rather simple and inexpensive, will be highly efficient and in every way desirable, particular attention being directed to the fact that the valve 10 65 does not gradually close, but is positively

held in completely open position until the instant when it should close, at which instant it is released and quickly shut. Thus, disadvantages well known to the art, resulting from slowly closing valves, are effectively overcome.

I claim:

1. The combination with a tank; of filling means therefor comprising a liquid inlet valve, means for quickly closing said valve when permitted to function, a lever operatively connected with said valve, and moved to a predetermined position by opening thereof, a latch for positively holding said lever in said position to hold the valve open, and means actuated by predetermined rise of liquid in the tank for automatically releasing said holding means.

2. The combination with a tank; of filling means therefor comprising a liquid inlet valve, means for quickly closing said valve when permitted to function, a lever operatively connected with said valve and moved to a predetermined position by opening thereof, a latch for positively holding said lever in said position to hold the valve open, and a liquid-lowered receptacle adjacent said latch adapted for connection with the tank to lower upon rise of liquid in said tank, said tank having a portion to release said latch when the receptacle lowers to a predetermined degree.

3. The combination with a tank; of filling means therefor comprising a base, a pipe pivotally mounted thereon for connection with the tank, a receptacle secured to and communicating with said pipe, an arched frame transversely straddling said receptacle and secured to said base, a weighted lever fulcrumed on the crown of said arched frame and connected with said receptacle for normally lifting the latter, a filling valve for the tank, means for closing said valve when permitted to function, a valve opening lever above the base and connected with the valve, a support upon which said lever is fulcrumed, said support rising from said base, a latch pivoted to one leg of said arched frame for holding said lever in valve-open position when moved to such position, means on said receptacle for releasing said latch when the receptacle lowers to a predetermined extent, and a one-way connection between said receptacle and said lever for moving the latter to valve-opening position as the receptacle ascends.

4. The combination with a tank; of filling means therefor comprising a base, a pair of bearings rising therefrom in spaced relation, a liquid supply line having its terminal supported by one of said bearings, said line having a valve, a coupling member between the two bearings and secured to said terminal, said coupling member having an outlet for connection with the tank and be-

ing provided with a cylindrical projection, a second coupling having a socket which receives said cylindrical projection, a short pipe member connected with said second coupling and rotatably supported by the other of said pair of bearings, piping swiveled to said pipe member and adapted for connection with the tank, a pipe rigidly connect-

ed with, communicating with and projecting laterally from said second coupling, and ¹⁰ controlling means for the aforesaid valve, including a receptacle with which the last named pipe is connected.

In testimony whereof I have hereunto affixed my signature.

WILLIAM H. SMITH.
